SHOE AND FOOT NORMALIZER

Harry Glen Hall, New York, N. Y.

Application November 7, 1929, Serial No. 405,377
Renewed May 18, 1933

3 Claims. (Cl. 36—71)

My invention relates to a normalizer which is adapted to be placed within a shoe for the purpose of affording the proper support to the wearer's foot.

5 Shoes for women's wear, as manufactured at present, are characterized by a high heel and a sharply curving instep portion. The sole proper of the shoe is integral with the instep portion, and at the junction between the sole and the in-
10 step, a recess is formed due to the height of the heel and the shortness of the instep. I have found that this recess is the cause of much dis-
comfort to the wearer of the shoe and has even more serious adverse effects, in that it tends to
15 poor posture and the various internal troubles that may be produced thereby.

The recess at the junction of the sole and instep portions of the present high-heeled shoes, hereinbefore mentioned, permits the metatarsal arch
20 of the wearer to sink to an abnormal position, and also causes the bony structure of the foot to be displaced from its normal alinement as well as the entire bony structure of the body.

In order to remedy the defects in shoes built
25 according to present designs, I provide a nor-
malizer to fill the recess characteristic of high-
heeled shoes, so that the wearer's foot is not per-
mitted to take up an abnormal position, but is
30 properly supported and maintained in its natural
position and curvature. The normalizer may be
made of leather, or any convenient substitute,
and is shaped to fit within the recess already de-
scribed. It is provided with a curved surface
35 conforming to the contour of the arch of the foot.
The normalizer may be placed within shoes al-
ready manufactured, over the inner sole thereof,
or may be placed between the outer sole and the
inner sole during the course of manufacture.

For a complete understanding of my invention,
40 reference is made to the accompanying drawing
illustrating a present preferred embodiment of
the invention. In the drawing,

Figure 1 is a partial-sectional view of a high-
heeled shoe having the invention applied thereto;
45 Figure 2 is a plan view of the support for the
right shoe;

Figure 3 is a transverse section along the line
III—III of Fig. 2; and

Figure 4 is a similar view along the line IV—IV.
50 Referring to the drawing, a high-heeled shoe of
ordinary design and construction is indicated at
10. The sole of the shoe includes a heel portion
11 overlying the heel proper 12, an instep portion
13, which is sharply arched to meet the sole por-
55 tion proper 14 which, of course, must be tangent

to the plane passing through the base of the heel
12. Because of the shortness of the instep portion
from the front edge of the heel to the rear edge
of the sole portion 14, and the considerable height
of the heel 12, a concave recess 15 is formed at the
intersection of the sole 14 with the instep portion
13. The depth of this recess depends to some
extent on the height of the heel 12, being greater
for greater heights of heels.

It will be obvious from Fig. 1 that, when the
wearer's foot is positioned within the shoe 10, the
recess 15 permits the foot to assume an unnatural
position such that the metatarsal arch is deformed
and the other bones of the foot are forced out of
normal alinement. The resultant cramping of
70 the wearer's toes may make it possible for a
smaller shoe to be fitted than can comfortably be
worn, because the toes are contracted by the
deformation referred to. The recess formed at
15 is the inducing cause of many foot troubles and
others of even more serious nature. The faulty
support afforded the metatarsal arch tends to
enlarge the ankles, and produces leg and back
aches and sacro-illiac strain. As before men-
tioned, it also tends to cause faulty posture and
80 places the foot bones in an abnormal relation
which brings on foot aches and callouses.

In order to remedy the disadvantages specified
hereinbefore which characterize the present style
of foot wear, I have invented a device illustrated
85 generally at 16 which I term a foot and shoe
normalizer. The shape of the normalizer 16 may
be best observed in Fig. 2. The normalizer is of
roughly triangular shape with its sides suitably
90 curved. The front edge is indicated at 17, and
18 and 19 indicate the inner and outer edges
thereof. The portion 20 rests on the curved
instep portion, as shown at 21 in Fig. 1. The
normalizer extends the full width of the shoe and
its shape varies with that of the recess 15.

95 The contour of the surfaces of the normalizer
will be apparent from Figs. 3 and 4, which are
sectional views along the lines III—III and IV—
IV, respectively, of Fig. 2. As shown in Fig. 3, the
normalizer has convex upper and lower surfaces
100 which are arched from side to side. The lower
surface 22 is given a more pronounced arch in
order to properly fill the recess 15. The upper
surface 23 is given a slight transverse arch, con-
forming to the natural curvature of the sole of
105 the wearer's foot.

In Fig. 4 is shown the longitudinal curvature
of the upper and lower surfaces of the normalizer.
The upper surface 23 has a slight longitudinal
curvature conforming to the arch of the wearer's
110

foot, while the lower surface 22 is so arched as to completely fill the recess 15.

As illustrated in Fig. 1, the normalizer is inserted into the recess formed in a manufactured shoe. The wearer's foot is indicated in outline at 24. The normalizer may be cemented or otherwise secured to the shoe, and as previously stated, may be placed therein during the course of manufacture. According to present methods of manufacture, however, it is impossible to eliminate the recess 15 without providing a filler, insert, or normalizer, such as that shown at 16, since the high heels now in vogue require a sharply curved instep portion, such as that shown at 13. The support may be formed from leather or any suitable substitute material, and its shape may be altered to conform to different styles and sizes of shoes. Instead of being solid, it may be hollow and formed from sheet material. While I have illustrated the normalizer in connection with a high-heeled shoe, it will be apparent that it has application to shoes of various styles and has utility even with shoes having comparatively low heels.

Among the numerous advantages which result from the use of the invention, may be mentioned the fact that it tends to reduce and strengthen abnormally large ankles. It also affords relief from leg and back aches, eliminates sacro-illiac strain, and tends to correct faulty posture. The proper support is given to the foot bones which are maintained in normal position so as to remove undue strain from the arches and ligaments. Since the destructive dip under the metatarsal arch of the wearer's foot is entirely removed by the use of the normalizer, the major cause of foot aches and callouses is eliminated. Improper fitting is prevented because the toes are maintained straight and if a short shoe is fitted, the wearer will immediately perceive the fact.

It will be apparent from an inspection of Fig. 1 that the foot indicated at 24 is supported in its normal position at all points. There is no destructive falling of the metatarsal arch adjacent

45

the recess 15, and the foot bones are in no way displaced from their normal position. All unnecessary strain is avoided, and the foot comfort of the wearer is markedly increased.

Although I have described but a single modification of the invention, it will be apparent to those skilled in the art to which it pertains that numerous changes and modifications thereof may be found desirable. It is, therefore, not my intention to be limited to the specific details of the described embodiment since any such changes which fall within the spirit of the invention may be made without departing from the scope of the appended claims.

I claim:

1. An arch support adapted to fill the recess formed between the shank and the substantially flat portion of a shoe sole, comprising a resilient member having a curved front edge substantially as wide as the interior of the shoe, a curved outside edge, and a substantially straight inside edge, the side edges tapering to a rounded rear end, said member having both its top and bottom surfaces curved transversely and longitudinally, the curvature of the lower surface exceeding that of the upper.

2. A device for normalizing the arch of a shoe and the foot of the wearer comprising a support adapted to fit in the recess between the flat portion and the shank of the sole of a shoe, the bottom of the support having a greater transverse curvature than the top and the top of the support having a greater longitudinal curvature than the bottom.

3. An insert for a shoe having a recess between the flat portion and the shank of its sole, comprising a resilient member of generally triangular shape having outwardly curving front, side, and rear edges and a substantially straight inner edge, the top of said member having a greater longitudinal curvature than the bottom, and the bottom having a greater transverse curvature than the top.
